UNITED STATES PATENT OFFICE.

JOHN HARRY REVESON, OF TERRE HAUTE, INDIANA.

SAFETY ATTACHMENT FOR BURNERS.

Application filed October 18, 1921. Serial No. 508,448.

To all whom it may concern:

Be it known that I, JOHN HARRY REVESON, a citizen of the United States, and a resident of Terre Haute, in the county of 5 Vigo and State of Indiana, have invented certain new and useful Improvements in Safety Attachments for Burners, of which the following is a specification.

My invention relates to improvements in 10 safety attachments for burners, especially gas burners for stoves, lamps, and the like, and it consists in the constructions, combinations and mode of operation herein described and claimed.

One of the foremost objects of the invention is to provide a simple but reliable 15 safety attachment for burners which prevents the escape of gas or other fuel from the burner unless such fuel is ignited.

A further object of the invention is to provide a safety attachment for burners which involves the necessity of applying a 20 lighted match to turn on the gas.

A further object of the invention is to 25 provide a safety attachment for burners in which the gas valve is held open by instrumentalities which are rendered active by heat radiating from the burner.

Other objects and advantages will appear 30 in the following specification, reference being had to the accompanying drawings, in which:—

Figure 1 is a diagram illustrating all of 35 the operating parts of the safety attachment,

Figure 2 is a perspective view of a gas 40 stove, illustrating the application of the improved safety attachment,

Figure 3 is a diagram illustrating the position of the expander relative to the burner 45 when the main gas inlet valve is wide open,

Figure 4 is a diagram illustrating the position of the expander relative to the burner when the main valve is nearly 50 closed,

Figure 5 is a longitudinal section of the controller, more fully described below,

Figure 6 is a detail perspective view of the rubber diaphragm, and

Figure 7 is a detail perspective view of the valve lifter.

It is the purpose of the invention to make use of heat for establishing and maintaining a flow of gas or other fuel to a burner. It is 55 necessary to apply a lighted match to an expander before a ball check valve will raise

to let the gas pass to a burner. It is also necessary to open the main gas valve in order to establish a flow of gas in the first place. The expander is carried by a part 60 of the valve and the former is automatically adjusted in relationship to the burner in accordance with the amount of opening of the main valve. Consider the diagram in Figure 1, which is a development of the 65 safety attachment clearly illustrating the operation. The main gas valve 1 is opened by turning the handle 2 (Figures 2 and 3), so that a flow of gas is established in the pipe 3 which leads to the top of the main 70 chamber 4 of the controller, where it is stopped by the ball check valve 5. The plug of the gas valve carries a lever 6.

As the gas valve 1 is opened, the lever 6 raises a crosshead 7, the lever having a bent 75 end 8 which operates in a horizontal slot 9 in the crosshead. The latter is guided by vertical rods 10 and there is sufficient friction between the vertical guides and the crosshead to maintain the latter in any adjusted position. This function is also aided by the friction of the plug in the gas valve.

The crosshead 7 carries a steel tube 11 which is surmounted by the expander 12. The expander consists of a closed can 80 containing air. Assume the expander 12 to be in the position illustrated in Figures 1 and 3, at which time the main valve 1 is opened wide.

A lighted match applied to the expander 90 12 will cause an expansion of the air and the inflation of a rubber diaphragm 13 in a supplemental chamber 14 of the controller, the diaphragm 13 having connection with the hollow tube 11 of the expander through 95 a flexible tube 15. The purpose of the flexible tube is to maintain communication between the expander and the diaphragm at all positions of the crosshead 7. Upon inflation of the diaphragm 13 (which takes but a very short time) the stem 16 is raised, in turn lifting the ball check valve 5 from its seat 17 and establishing the flow of gas from the pipe 3 to the burner B. The gas now escaping at the burner should be ignited.

Heat radiating from beneath the burner B will keep the air in the can 12 expanded, and consequently keep the ball check valve 5 raised so that the flow of gas may continue. It may be desired to turn the gas 110 down so as to produce a low flame. The

handle 2 should be turned toward the right in Figure 3. This will raise the crosshead 7 through the lever 6 so as to bring the expander 12 closer to the burner. The diminution in heat radiated from the burner, is compensated for by the reduction in space between the burner and the expander, the result being substantially that obtained before, namely, the air in the expander column 10 is kept heated and the valve 5 is kept elevated.

The diagrams in Figures 3 and 4 illustrate the adjustment of the expander 12 in relationship to the burner B in proportion to the amount of opening of the main gas valve. The amount of travel of the expander equals the radius of the lever 6 which is made to assume its extreme position in a vertical line by turning the handle 2 from its normal rest position at right angles to the left of the pipe 3 to a similar right angular position at the right of the pipe 3. When the handle 2 is in the first position, the crank 6, crosshead 7 and expander 12 are at the extremity of their lowermost movements and the valve 1 is closed. When these parts are moved to approximately the mid position (Figure 3) the valve 1 is wide open, and when the handle 2 is moved to the latter position, the crank 6, crosshead 7 and expander 12 are at the upper extremity of their movements. The main valve 1 is then again closed.

In addition to the parts described above, the controller 4 has a circular base 17 from which stems 18 depend (Figures 1 and 3) for the purpose of supporting a yoke 19. This yoke has a boss in which a screw 20 is threaded for the purpose of holding the supplemental chamber 14 in place.

This supplemental chamber comprises a short section of glass tubing (Figure 5) which engages rubber washers 21 at both edges, for the purpose of making gas-tight joints. The upper washer is seated in a recess in the base 17. The lower washer is seated in a recess in the entrance plate 22 which includes the chamber 23 to which the heated or expanded air from the expander 50 12 is admitted.

The screw 20 enables removing the entrance plate 22 and its carried parts, so that the diaphragm or balloon 13 may be renewed. The rubber of which this diaphragm is made dries out in time so that it requires to be replaced. Figure 6 shows one of the diaphragms in place on the entrance plate. The diaphragm includes a metal base 24 which is screwed in place on the threaded stud 25 in the center of the plate 22.

In order that access may be had to the ball valve 5, lifter 16, etc., the controller 4 is made in sections as shown in Figure 5. The various parts are unscrewed for the purpose described. The stove to which the

improved safety attachment is applied, is shown in a conventional manner in Figure 2 but may be briefly described as comprising upper and lower tables 26 and 27. The rods 28 separate the tables and rods 29 support the burner structure. The table 26 furnishes a bearing or guide for the vertically movable steel tube 11. The table 27 furnishes a base for the guide 10.

While the construction and arrangement of the improved safety attachment for burners as herein described and claimed, is that of a generally preferred form, obviously modifications and changes may be made without departing from the spirit of the invention or the scope of the claims.

I claim:—

1. A gas valve having means for moving a device containing a thermally sensitive substance into a predetermined relationship with a burner as the valve is turned, and means which is influenced by the expansion of said substance by the application of heat to said device to establish a flow of gas from the valve to the burner.

2. The combination of a valve for supplying a burner with fuel, and a device containing a thermally sensitive substance adapted to assume various positions in respect to the burner in accordance with the amount of opening of the valve.

3. The combination of a valve for supplying fuel to a burner, and means which is moved as the valve is turned to in turn position a device containing a thermally sensitive substance in respect to the burner and in proportion to the position of the valve so that it may receive a substantially constant quantity of heat.

4. Slidable means supporting a device containing a thermally sensitive substance, a valve primarily controlling the flow of fuel to a burner, means for moving the slideable means as the valve is moved to position said device in respect to the burner in accordance with the amount of opening of the valve, and a secondary gas control valve held open by the expansion of said substance while fuel escaping at the burner remains ignited.

5. A valve secondarily controlling the flow of fuel to a burner, a device containing a substance rendered sensitive by heat from the burner to keep said valve open, and a valve primarily controlling the flow of fuel, including means for adjusting said device closer to the burner as the primary valve is moved toward a closed position.

6. In combination with a burner, manually and thermally operated means cooperating to maintain a fuel flow while ignited fuel is escaping from the burner, and means which keeps the thermal means operative, adjusted in respect to the burner by the operation of said manual means.

7. A valve held open by the effect of heat from a burner to which it admits fuel, and a device which is adjustable in respect to the burner to maintain said effect regardless of variations in the radiant heat, including a flexible connection which maintains the communication between said device and the burner.

8. In combination with a burner, a valve which controls the flow of fuel to the burner, another valve which controls the flow of fuel to the first valve, a diaphragm containing a thermally sensitive substance for moving the first valve, and a device containing some of said substance having communication with that of the diaphragm adapted to be moved into a location to receive a predetermined amount of heat from the burner when said other valve is moved, but requiring the application of a lighted match to open the first valve before fuel can escape at the burner for ignition.

9. A valve which controls the flow of fuel to a burner, an expander which is adjustable in respect to the burner, and a flexible connection from the expander to a diaphragm, all containing a thermally sensitive substance, which keeps the valve open by the effect of heat from the burner on the substance in the expander.

10. In combination with a burner, a valve which controls the flow of fuel to the burner, a crosshead carrying an expander, another valve controlling the flow of fuel to the first valve and shifting the crosshead as it is turned to adjust the expander in respect to the burner, and a diaphragm with a flexible connection to the expander forming a container with the expander of a substance sensitive to heat from the burner to flex the diaphragm and open the first valve.

11. In combination with a burner, an expander carried by a crosshead which moves on guides, and a fuel valve with means in connection to move the crosshead and adjust the expander in respect to the burner.

12. In combination with a burner, a thermostatic fuel controlling apparatus in-

cluding an expander containing a thermally sensitive substance, and a valve with means for moving the expander closer to the burner as the valve approaches a closed position, and vice versa.

13. In combination with a burner, a controller having a fuel conduit leading to the burner, a valve in the controller for checking the passage of fuel to the conduit, a diaphragm for moving the valve, having communication with an expander both of which contain a thermally sensitive substance which is influenced by heat from the burner to flex said diaphragm; and a gas-tight container for the diaphragm in which it flexes to move said valve.

14. In combination with a burner, a controller having a fuel conduit leading to the burner, a valve in the controller for checking the passage of fuel to the conduit, a diaphragm for moving the valve, having communication with an expander both of which contain a thermally sensitive substance which is influenced by heat from the burner to flex said diaphragm; a gas-tight container for the diaphragm in which it flexes to move said valve, and means for applying pressure to said container to make it gas-tight.

15. A controller for fuel for a burner, comprising a compartment with a valve, a second compartment with a conduit leading to the burner, a third compartment having a diaphragm containing a thermally sensitive substance, and lifting means extending from the first to the last compartment to displace the valve when the substance in said diaphragm is affected by heat.

16. A controller for fuel for a burner, including means for lifting a valve which controls the flow, a diaphragm containing a thermally sensitive substance for moving said means, and a cylinder, including a plate at which said substance has an entrance, held in place on the controller by compression means which provides a gas-tight joint for the diaphragm.

JOHN HARRY REVESON.
